UNITED STATES PATENT OFFICE.

JOSEF GAIRING, OF RIEDLINGEN-ON-THE-DONAU, GERMANY.

FUEL-CHARGING DEVICE FOR BRICKKILNS.

Application filed September 5, 1923. Serial No. 661,117.

To all whom it may concern:

Be it known that I, JOSEF GAIRING, a citizen of the German Republic, and resident of Riedlingen-on-the-Donau, Wurtemberg, Germany, have invented a new and useful Improved Fuel-Charging Device for Brick-kilns, of which the following is a specification.

There exist already charging devices for brick-kilns in which the fuel is conveyed from the coal receptacle into the kiln by means of conveying worms, stirring blades, drivers, or the like. The present invention is distinguished from said known devices by a rotary disk forming the bottom of the coal receptacle and being provided with an opening through which the fuel is fed into the kiln, the fuel being uniformly distributed over the area of said disk or bottom and it being rendered possible to let pass also comparatively large pieces of coal; besides, the manner of operation is more reliable.

The rotatory bottom is provided at its lower surface with a sloping curved guide plate extending from the front edge of the opening mentioned below it in rearward direction, relatively to the direction of rotation of the bottom, and terminating at some distance behind the rear edge of the said opening. The object of this guide plate is to prevent the coal from falling either directly upon the bottom of a casing located below it, or, may be, directly into the stoking neck of the kiln. Besides the said curved plate, another curved plate is attached to the lower surface of the rotatory bottom, but this other plate or wall is arranged vertically and extends partly along the inner edge of the first-mentioned plate in horizontal direction which, however, changes according to the curvature of said inner edge; vertically, the other curved plate extends to the bottom of the casing below it which contains the two plates in question, and that part or half which is not in contact with the inner edge of the sloping guide plate forms a vertical wall at some distance behind the rear edge of this plate, that wall forming a vertical channel through which the coal passes on its way down into the kiln. The vertical plate or wall is of S-shape, one part of the S being in contact with the sloping guide plate, the other part forming the vertical channel.

The just-mentioned plate need not ac-

tually be perfectly vertical at any rate. It may be a little inclined so that the channel mentioned is correspondingly conical at that wall formed by the said plate. The inclined part of the wall is preferably that opposite the free edge of the sloping guide plate and the direction of the inclination is such that the passage of the coal through the said channel is facilitated. The sloping guide plate is preferably shaped similar to a part of the thread of a screw. Another constructional member of the device consists of a tightening ring of angular section which is affixed to the lower rim of the fuel receptacle to which the rotatory bottom pertains, and the horizontal flange of which is directed inwards and extends over the rim of said bottom, as is all illustrated in the accompanying drawing in which my invention is illustrated diagrammatically by way of example, and in which Figure 1 is a vertical section of the charging device, Figure 2 is a plan of this device; Figure 3 is a side-view and Figure 4, a perspective view of the rotatory bottom, its sloping guide-plate, and its vertical S-shaped wall; Figure 5 is also a vertical section through the entire charging-device, the plane of section lying at right angles to that of Figure 1; Figure 6 is a plan of the rotatory bottom, and Figure 7 a bottom-view thereof.

2 is the fuel receptacle, and 4 is a casing carrying it. Centrally within the casing is a vertical shaft 10 which is firmly connected with the rotatory bottom 1 rotated by said shaft and on and over which the fuel distributes uniformly while the bottom is rotated. This latter is provided with an opening 3 through which the coal passes into the casing 4, and from the edge of this opening extends rearwards and downwards a sloping and curved guide plate 11. At the inner edge of this plate is a vertical wall 5 which is affixed to the lower surface of the bottom 1 and is S-shaped, one half or part of the S being in contact with the inner edge of the guide plate 11, whereas the other half or part extends farther rearwards and finally practically radially outwards, towards the inner surface of the casing 4. This part of the vertical wall which is located opposite the rear edge of the guide plate 11 forms a vertical channel through which the coal passes when leaving the plate 11. This latter and the wall 5 rotate, of course, together with the bottom 1, and this being so,

the coal lying on the bottom of the casing 4 is conveyed along over this bottom in a circular path until it arrives at the stoke neck 6 of the brick-kiln.

5 That part of the wall 5 which is not in contact with the guide-plate 11 may be a little inclined in order to facilitate conveying the coal into the neck 6.

This charging procedure is repeated at 10 every rotation of the bottom 1 with its members 5 and 11, but the device may be modified in such a manner that continuous charging is obtained. The only changes necessary to that effect would consist in arranging the 15 neck 6 in the centre part of the bottom of the casing 4, conducting the charging channel formed by the parts 5 and 11 to that central neck, and rotating the bottom 1 with its parts 5 and 11 from above instead of 20 from below.

The sloping guide plate 11 is preferably shaped like a part of a thread of a screw in order to obviate checking of the coal sliding down on and along over it.

25 9 is a ring of annular section which forms a tightening member for the bottom 1 in that its inwardly directed horizontal flange extends over the rim of the bottom. This ring is affixed to the lower rim of the 30 receptacle 2.

The vertical shaft 10 is supported by the bearing 6 and guided by the guide bearing 7. Both bearings are located below the casing 4 whereby they are prevented from being affected and, perhaps, destroyed by the coal or the heat, as is often times the case with the known charging devices for brick-kilns.

I claim:

40 1. A fuel charging device for brick-kilns, comprising, in combination, a fuel receptacle, a rotatory fuel receptacle bottom having a discharge opening, a stationary casing with a stationary bottom and a discharge 45 opening therein below said receptacle and its bottom, a sloping guide plate attached to the lower surface of the rotatory bottom at the front edge of the opening thereof and extending rearwards down into said casing, a practically vertical wall also attached to the lower surface of the rotatory bottom and extending partly along the inner edge of the said sloping guide plate and terminating horizontally behind the rear edge thereof and at some distance therefrom, and vertically near the bottom of the 50 said stationary casing.

55 2. A fuel charging device for brick-kilns, comprising, in combination, a fuel recep-

tacle, a rotatory fuel receptacle bottom having a discharge opening, a stationary casing with a stationary bottom and a discharge opening therein below said receptacle and its bottom, a sloping guide plate attached to the lower surface of the rotatory bottom at 60 the front edge of the opening thereof and extending rearwards down into said casing, a practically vertical wall also attached to the lower surface of the rotatory bottom and being S-shaped in horizontal section, one 65 part of the S extending along the inner edge of the said sloping guide plate, the other part terminating horizontally behind the rear edge thereof at some distance therefrom, and vertically near the bottom of the said 75 stationary casing.

3. A fuel charging device for brick kilns, comprising, in combination, a fuel receptacle, a rotatory fuel receptacle bottom having a discharge opening, a stationary casing with a stationary bottom and a discharge opening therein below said receptacle and its bottom, a sloping guide plate having the shape of a part of a screw-thread and being attached to the lower surface of the 80 rotatory bottom at the front edge of the opening thereof and extending rearwards down into said casing, a practically vertical wall also attached to the lower surface of the rotatory bottom and extending 85 partly along the inner edge of the said sloping guide plate and terminating horizontally behind the rear edge thereof at some distance therefrom, and vertically near the bottom of the said stationary casing. 95

4. A fuel charging device for brick-kilns, comprising, in combination, a fuel receptacle, a rotatory fuel receptacle bottom having a discharge opening, a stationary casing with a stationary bottom and a discharge opening therein below said receptacle and its bottom, a tightening ring so arranged as to be adapted to close the joint between the rim of the rotatory bottom and the opposite wall part, a sloping guide plate attached to the lower surface of the rotatory bottom at the front edge of the opening thereof and extending rearwards down into said casing, a practically vertical wall also attached to the lower surface of the rotatory bottom and extending partly along the inner edge of the said sloping guide plate and terminating horizontally behind the rear edge thereof at some distance therefrom, and vertically near the bottom of the said 100 stationary casing. 110

JOSEF GAIRING.
